(57) **CLAIM**

The ornamental design for a reload kit cap for fire extinguisher, as shown and described.

DESCRIPTION

FIG. 1 is a top perspective view.

FIG. 2 is a side plan view.

FIG. 3 is a front plan view.

FIG. 4 is an other side plan view.

FIG. 5 is a rear plan view.

FIG. 6 is a bottom plan view; and,

FIG. 7 is an another top perspective view.

Broken lines in the drawings are included for the purpose of illustrating an environment and form no part of the claimed design. The claimed invention can be used in other environments.

1 Claim, 7 Drawing Sheets
